UNITED STATES PATENT OFFICE

126,394

DESIGN FOR A TELEPHONE STAND

Jerome Hirshfeld, New York, N. Y.

Application December 26, 1940, Serial No. 97,614

Term of patent 14 years

To all whom it may concern:

Be it known that I, Jerome Hirshfeld, a citizen of the United States, residing in the city, county, and State of New York, have invented a new, original, and ornamental Design for a Telephone Stand, of which the following is a specification, reference being had to the accompanying drawing, forming part thereof.

The figure is a perspective view of a telephone stand, showing my new design.

I claim:

The ornamental design for a telephone stand, as shown,

JEROME HIRSHFELD.
